DESIGN FOR A ROLLING CLOWN BALL

Leonard Z. Plebanek, Chicago, Ill.

Application October 10, 1945, Serial No. 122,724

Term of patent 3½ years

(Cl. D34—15)

To all whom it may concern:

Be it known that I, Leonard Z. Plebanek, a citizen of the United States, residing at Chicago, in the county of Cook and State of Illinois, have invented a new, original, and ornamental Design for a Rolling Clown Ball, of which the following is a specification, reference being had to the accompanying drawing, forming a part thereof.

Figure 1 is a side elevational view of a rolling clown ball embodying my new design;

Figure 2 is an end elevational view of the rolling clown ball shown in Figure 1; and

Figure 3 is a top plan view.

I claim:

The ornamental design for a rolling clown ball, as shown.

LEONARD Z. PLEBANEK.
